UNITED STATES PATENT OFFICE.

WILLIAM R. MILLER, OF PITTSBURG, PENNSYLVANIA, ASSIGNOR TO THE FORTER-MILLER ENGINEERING COMPANY, OF PITTSBURG, PENNSYLVANIA, A CORPORATION OF PENNSYLVANIA.

REGENERATIVE MUFFLE-FURNACE.

No. 805,372.

Specification of Letters Patent.

Patented Nov. 21, 1905.

Application filed November 23, 1904. Serial No. 234,085

To all whom it may concern:

Be it known that I, WILLIAM R. MILLER, a citizen of the United States, residing at Pittsburgh, in the county of Allegheny and State 5 of Pennsylvania, have invented certain new and useful Improvements in Regenerative Muffle-Furnaces, of which the following is a specification, reference being had therein to the accompanying drawings, forming part of 10 the specification, in which—

Figure 1 is a front elevation, partly in section, indicated by the line I I of Fig. 2, showing my improved regenerative muffle-furnace. Fig. 2 is a horizontal sectional view indicated by the line II II of Fig. 1. Fig. 3 is a vertical sectional view on the line III III of Fig. 5. Fig. 4 is a similar view on the line IV IV of Fig. 5. Fig. 5 is a horizontal sectional view on the line V V of Fig. 1.

20 My invention refers to improvements in regenerative muffle-furnaces, having for its object to supply heat of combustion by radiation to one or more furnace-chambers inclosed within comparatively thin walls, 25 around which the gases of combustion circulate, the structure embodying regenerative checker-work of the usual Siemens construction, together with the customary supply and exhaust mains and flues, reversing 30 valves, &c.

The class of work to which the furnace is particularly applicable is the annealing of porcelain-lined ware, as bath-tubs, &c., and similar articles requiring a continued exposure 35 to a regular heat of high degree. It is also essential that all parts of the radiating-chambers shall be subject to substantially the same heat. In recuperative furnaces or 40 other constructions where the heat is continuously supplied from one side and circulates uniformly in one direction such a regular diffusion and consequent resulting action are impossible, nor can a sufficiently high degree of heat be attained or maintained. By 45 my construction I utilize regenerating-chambers so arranged with relation to the furnace-chambers as to provide a circulating course for the gases of combustion in one direction for a given period and of then reversing the circulation, as shall be herein-after described, so as to secure the objects in view, the entire apparatus being arranged and designed to secure the best and most

economical results with a view of continuous operation of the furnace and the work to be done.

Referring now to the drawings, 2 represents the gas-chamber, and 3 the air-chamber, of a Siemens furnace, to which gas and air, respectively, are furnished—the gas from 65 a gas-main 4 through the reversing-valve 5. and flue 6, the air from valve 7 and flue 8. It will be understood that these furnaces, as usual, are built in pairs, as shown, whereby the incoming air and gas become heated by 65 passing through the checker-work and after circulating around the radiating-flues give up their latent heat, which is absorbed by the checker-work of the opposite side, the waste gases passing outwardly to the chimney-flue 9 through the registering-valves. This construction does not *per se* form any 70 part of my present invention, being well known and understood without further description.

75 Located above the regenerative chambers, preferably at each side, are the heating-chambers 10, of suitable size and shape to receive the article to be annealed, provided with the customary doors 11 and suitable 80 raising mechanism. (Not shown.) Entirely surrounding and inclosing the chamber 10 is a thin wall 12, arched at the top and having vertical sides, composed of suitable brick or refractory material. These side walls preferably converge toward each end of the furnace longitudinally, as shown in Fig. 2, providing barrel-shaped chambers. Outwardly beyond the wall 12 and preferably corresponding therewith in arrangement are the 85 surrounding walls 13, between which and wall 12 are a series of intervening arched ports or passages 14, through which the gases 90 of combustion circulate, as indicated by the arrows, transverse partition-walls 15 being 95 interposed at intervals to strengthen the structure, thus providing a plurality of closely-adjacent flues. All of these ports 14 communicate at opposite sides by downward extensions 14' with the common combustion-chambers into which the gas and air passing 100 from the checker-work are discharged, and it will thus be seen that the circulation of such gases is continuously around the exterior of the thin partitions 12, the entire inner area 105 of furnace-chambers 10 being thus exposed

to radiated heat. After a short interval of time the valves are reversed, causing a consequent reversal of the circulation, practically without interruption, and by this means

5 the articles contained in the radiating furnace-chambers 10 are subjected to a very even continuous heat, which is of the highest efficiency for the purpose of annealing or similar work.

10 It will be understood that the entire furnace construction is reinforced and stayed by suitable buckstaves, tie-rods, &c., and when thus constructed it is capable of producing the most beneficial results in the manner noted.

15 The furnaces are most economically and advantageously built in pairs or series of pairs, as shown, although it is obvious that but a single radiating-furnace may be used 20 with the regenerative chambers shown and that the number of heating-chambers with relation to the regenerative chambers is not necessarily fixed, but may be varied to suit different requirements or use. The arched 25 partitions 12 and the corresponding ports 14 may be of semicircular form, as shown, or of other degree of curvature, as desired, according to the conditions of use, &c.

Other changes or variations in the design, 30 construction, or various details may be made by the skilled mechanic without departing from the scope of the following claims.

What I claim is—

1. The combination with the chambers of 35 a regenerative furnace, of a radiating heating-chamber inclosed within surrounding side walls and an arched roof, an outer surrounding wall conforming thereto, with intervening continuous arched gas-circulation ports communicating with the regenerative chambers, 40 substantially as set forth.

2. The combination with the chambers of 45 a regenerative furnace, of a radiating heating-chamber inclosed within surrounding side walls and an arched roof, an outer surrounding wall conforming thereto, with intervening continuous arched gas-circulation ports com-

municating with the regenerative chambers, with a series of transverse strengthening-partitions providing a plurality of parallel circulating-gas ports, substantially as set forth. 50

3. The combination with a pair of regenerative chambers provided with gas and air inlet ports and radiating checker-work, of superimposed chambers provided with arched surrounding thin inclosing walls, outer surrounding walls, and continuous intervening arched gas-circulation ports communicating at opposite sides of the regenerative furnace-chambers, and traversing the exterior of the chamber-inclosing radiating walls, substantially as set forth. 55 60

4. The combination with a pair of regenerative chambers provided with gas and air inlet ports and radiating checker-work, of superimposed chambers provided with surrounding thin inclosing walls, outer surrounding walls, and continuous intervening gas-circulation ports communicating at opposite sides of the regenerative furnace-chambers, and 70 traversing the exterior of the chamber-inclosing radiating walls, with transverse strengthening-partitions dividing the gas-circulation openings, into a series of parallel flues, substantially as set forth. 75

5. The combination with a pair of regenerative chambers provided with checker-work and gas and air inlet ports, of a plurality of superimposed radiating-chambers formed by thin vertical side walls arched at the top 80 and converging toward each end, outer side walls similarly arched at the top and providing a connected series of intervening arched continuous gas-circulating ports, with downwardly-extending ports communicating with 85 the regenerative chambers at the outer sides of the radiating-chambers respectively, substantially as set forth.

In testimony whereof I affix my signature in presence of two witnesses.

WILLIAM R. MILLER.
